UNITED STATES PATENT OFFICE.

AXEL JOHNSON, OF OAKLAND, CALIFORNIA.

FUEL ECONOMIZER.

1,412,208.

Specification of Letters Patent. Patented Apr. 11, 1922.

Application filed June 2, 1921. Serial No. 474,541.

To all whom it may concern:

Be it known that I, AXEL JOHNSON, a citizen of the United States, residing at the city of Oakland, in the county of 5 Alameda and State of California, have invented certain new and useful Improvements in Fuel Economizers, of which the following is a specification.

Fuel economizers as at present constructed 10 and used particularly in connection with gas and vapor stoves are open to many objections, the principal one being that both chambers of the economizer cannot be employed in connection with the heating of the 15 same vessel, for example an oblong vessel, such as a roasting pan or wash boiler, which would overlap both chambers.

The present invention relates to an improved fuel economizer wherein the upper 20 wall of both chambers lie in substantially the same plane and are connected with a flue having a relatively flat upper surface which is also disposed in substantially the same plane as the upper edges or surface 25 of the chamber forming walls.

This construction enables the utilization of the heat from the burner chamber to heat one portion of an oblong vessel and the heat passing through the flue and into the heated 30 chamber for heating another portion of the same oblong vessel.

Another object is to provide in connection 35 with the heated chamber,—a grill or toaster, permanently associated therewith and adapted for folding into closed position when not in use, to form a relatively flat surface for the upper end of the heated chamber. A further object is to provide a construction formed of strap material with 40 parallel edges enabling the manufacture of the device at little cost.

With the above mentioned and other objects in view, the invention consists in the novel construction and combination of parts 45 hereinafter described, illustrated in the accompanying drawings and pointed out in the claims hereto appended; it being understood that various changes in the form, proportion, size, and minor details of construction within the scope of the claims may be resorted to without departing from the spirit

or sacrificing any of the advantages of the invention.

To more fully comprehend the invention, reference is directed to the accompanying 55 drawings, wherein—

Fig. 1 is a view in perspective of the preferred embodiment of my invention.

Fig. 2 is a longitudinal sectional view of the invention in use and positioned over one 60 burner of a stove.

Fig. 3 is a transverse sectional view through the flue on line 3—3 of Fig. 1.

Referring more particularly to the drawings, wherein like characters of reference 65 designate corresponding parts—1 indicates a metallic strap or band having parallel top and bottom edges and fashioned to simulate substantially a figure 8, one loop of which forms a burner chamber 2 and 70 the other loop of which forms a heated chamber 3, the intermediate connecting portions of the band being disposed in parallel relation as at 4, forming the side walls of a heat conducting flue. 75

The portions 4 are connected by the flanged plate 5 forming a flue top wall and a similar plate 6 forming a flue bottom wall, said top and bottom walls lying in substantially the same plane as the upper edges 80 of the curved portions 7 and 8 of the band 1 forming the chambers 2 and 3.

The portions 7 and 8 of the band 1 are surrounded in spaced relation by auxiliary bands 9 and 10 bent inwardly as at 11 at 85 their terminals and attached, as at 12, to the portions 4 of the member 1, this being clearly illustrated in Fig. 1 of the drawings.

Between the outer surface of the member 1 at points 7 and 8 and the inner surface of the member 9, are the yieldable spacer member 13 also formed of strap or sheet material consisting of a base 14 and curved wings or terminals 15 contacting with the 95 inner surface of the members 9 and 10. Each spacer is adapted to be secured in position as at 16 and the upper edges of the bases 14 and wings 15 of the spacer associated with the heated chamber 3 are adapted to 100 extend slightly above the upper surface of the portion 8 of the band 1 and above the

upper edge of the member 10, providing an exit passage or discharge 14' for the heat between the open top of the chamber 3 and the bottom of a receptacle or container 15' positioned thereover.

As in Fig. 2—the upper surface of the spacers associated with the chamber 2 lie flush with or fall short of the upper edge of the portion 7 of the member 1, whereby on 10 the positioning of a pot or kettle 16' over the chamber 2, the heat from the burner 18 will be prevented from escaping around said pot or kettle.

Transversely of the chamber 3 and pivoted through openings 19 in the portion 8 of the member 1 is a grill or toaster 20, formed at its lower end with the material supporting prongs 21 and when in use the free end 22 of said grill or toaster is adapted 20 to be raised at an angle, whereby the heat passing through the flue will be directed against the material held thereon.

It will be apparent that this invention provides a construction wherein the supporting 25 surface for the pot or kettle and the upper wall surface 5 of the flue are all disposed in substantially the same parallel plane, enabling the use of the device with separate 30 pots or kettles 15' and 16' or the use of a single oblong kettle, not shown, which is adapted to overlie both chambers 2 and 3.

Having thus described my invention what I claim as new and desire to secure by Letters Patent of the United States is:—

35 1. A fuel economizer consisting of a conducting flue, a pair of metallic bands secured at their opposite ends to the opposite sides of corresponding ends of said flue, said pairs of bands being bent into circular form 40 and disposed in spaced concentric relation, providing at opposite ends of said flue substantially duplicate multiple walled chambers open at their top and bottom with

corresponding faces in a plane substantially parallel with corresponding faces of said 45 conducting flue, said conducting flue adapted for conducting heat from one chamber to the other, the top surface of said conducting flue being relatively flat.

2. A fuel economizer consisting of a pair 50 of walled chambers open at their top and bottom, a flue connecting said chambers at one side to permit the transference of heat from one chamber to the other, said flue consisting of top, bottom and side walls, the top 55 being relatively flat and disposed in substantially the same plane as the upper edge of the chamber forming walls, a band extending around the portion of the outer wall surface of one chamber forming wall and 60 spaced therefrom, and spacer members separating the chamber wall and band, the upper edges of certain of said spacers lying in a plane above the top edge of said chambers.

3. A fuel economizer consisting of a pair 65 of metallic chambers open at their top and bottom and each formed of a pair of circularly bent bands disposed in concentric relation, a flue connecting said chambers, one at each end, said flue being open at its ends 70 to the interior of said chambers and closed at its top, bottom and sides, with its top and bottom walls horizontally disposed respectively in substantially the same planes as the upper and lower edges of the bands 75 forming the chamber walls, and means between the bands of one chamber and projecting slightly above the same to provide a space beneath the receptacle base and the upper edge of the band to permit of the escape of the heat conducted to said chamber around said receptacle.

In testimony whereof I have signed my name to this specification.

AXEL JOHNSON.
